UNITED STATES PATENT OFFICE.

MURRAY ALBERT KANE, OF JOHNSTOWN, PENNSYLVANIA.

FLAG HOLDER FOR THE MOTOMETERS AND SIMILAR DEVICES OF AUTOMOBILES.

Application filed March 13, 1926. Serial No. 94,503.

This invention relates to flag holders for the motometers and similar devices of automobiles and has for an important object thereof the provision of a device of this character formed in sections which may be stamped by a single operation from a sheet of metal.

A further object of the invention is to provide a device of this character in which the sections are held together by securing elements so that they clamp not only upon the elements to be held but upon the element to which the first named elements are to be attached.

15 These and other objects I attain by the construction shown in the accompanying drawing, wherein for the purpose of illustration is shown a preferred embodiment of my invention and wherein:—

20 Figure 1 is an edge elevation showing a flag holder constructed in accordance with my invention applied to a motometer;

Figure 2 is a front elevation of one of the sections;

25 Figure 3 is a vertical sectional view through one of the sections;

Figure 4 is an enlarged detail plan view showing the manner in which the sections clamp together upon the flag staffs.

30 Referring now more particularly to the drawings, the device is in the form of a plate 10 having formed therein an opening 11 which opens through one edge of the plate. At the edge of the plate, the opening

35 11 is restricted. About the edges of this opening, the plate is offset, as at 12, for a distance approximately equal to one-half the thickness of the element E to which the device is to be attached, at present disclosed as a motometer. The body of the plate exteriorly of the offset producing the flange 11^a has formed in the opposite face thereof from said flange 11^a a series of concentered depressions 13, one of these depressions be-

40 45 50 55 ing arranged substantially upon the vertical axis of the element E to which the device is to be applied when the device is in applied position. These depressions are preferably formed by swaging the material of the plate, as more clearly shown in Figure 4. Intermediate these depressions, the plate has formed therethrough openings 14 for the passage of securing elements such as small bolts by means of which the two sections of the completed flag holder are held in assembled relation.

It is pointed out that these securing elements 14 provide at the same time a means for clamping the sections together upon the stems of flags or similar ornaments and for 60 clamping the sections together upon the element E. It is further pointed out that when these sections are clamped together, due to the fact that the shape of the offset flange 12 conforms to the shaping of the element E and embraces this element at opposite sides of the point of greatest width thereof, the sections are rendered unremovable until the securing elements shall have been removed.

70 It will be obvious that a device of this character may be very cheaply and readily produced and is very readily applied to a motometer or similar ornament.

I claim:—

1. A flag holder for use with motometers and the like comprising two sections each formed from a sheet of metal having an opening extending to one edge thereof and being formed about the edges of the opening with an offset flange, the body of the sheet being provided with a depressed portion, said depressed portions combining in the assembled relation of the sections to produce a socket for the reception of a staff 80 and securing elements directed through said sections for clamping the sections upon the staff and upon the ornament to which they are applied.

2. A flag holder for use with motometers 90 and the like comprising two sections each formed from a sheet of metal having an opening extending to one edge thereof and being formed about the edges of the opening with an offset flange, the body of the 95 sheet being provided with a depressed portion, said depressed portions combining in the assembled relation of the sections to produce a socket for the reception of a staff and securing elements directed through said 100 sections for clamping the sections upon the staff and upon the ornament to which they are applied, the offset flange conforming in shaping to the element to which the holder is to be applied, the opening of each sheet 105 being restricted at the edges of the sheet.

In testimony whereof I hereunto affix my signature.

MURRAY ALBERT KANE.
